UNITED STATES PATENT OFFICE.

ADOLPH W. MALONE, OF FILLMORE, UTAH, ASSIGNOR OF ONE-HALF TO ALBERT H. VESTAL, OF ANDERSON, INDIANA.

METAL POLE.

Application filed August 19, 1926. Serial No. 130,285.

My invention relates to an improved construction of metal poles or posts for use in the construction of telephone and telegraph lines, fence construction, and for 5 any other purposes for which such poles may be found appropriate, whereby such a pole or post is provided of a minimum weight and maximum carrying strength, and also one that will be durable and substantially 10 permanent in use, and by the use of which the disadvantages experienced in the use of wooden poles and posts are obviated, all as will be hereinafter more fully described and claimed.

15 Referring to the accompanying drawings which are made a part hereof and on which similar reference characters indicate similar parts,

Figure 1 is an elevation of a complete pole 20 set into the ground,

Figure 2, a detail perspective of the lower end of the pole,

Figure 3, a diagrammatic plan view of the top of the pole, and

25 Figure 4, a detail view of other forms of angle irons that may be employed.

In the accompanying drawings a pole or post of my improved construction is shown constructed of a series of members or strands 30 L-shaped in cross-section, a portion of which extend in a spiral direction lengthwise of the pole and another portion extend lengthwise of the pole in a spiral direction reverse to that of the first portion.

35 In the drawings the outside members 5 are formed into a left-hand spiral and the inner members 6 are formed into a right-hand spiral, there being seven members extending in each direction and crossing each 40 other at intervals throughout the length of the pole. The flat faces of the inner members and outer members bear against each other at the crossing points, as shown most clearly at the top of Figure 2, at which 45 points the members are secured together by any approved method but preferably by electric welding, although riveting or any other approved method may be employed if desired.

50 At the extreme bottom of the post or pole is a wide strong metal band 7 to which the lower ends of the members 5 and 6 are secured, and at a distance above the bottom another similar band 8 is provided to which 55 said members are likewise secured, the band

8 being placed at the ground line or at the point where the greatest strain is placed upon the post in use. It will be understood, of course, that the bands 7 and 8 are of such width as may be appropriate for the particular character of pole and particular use to which it is to be put, and also that the members 5 and 6 are of appropriate size to make a post or pole of the strength and 60 rigidity desired for any special purpose. 65

By reason of the special form of the members 5 and 6 secured together in a spiral form as shown, a pole with a comparatively small amount of metal is provided capable of carrying a comparatively great strain, the 70 angles of the members being so positioned that each member supplements the other in resisting strain and lending strength and rigidity to the structure.

A similar band 9 is placed at the top of the 75 pole to which the upper ends of the members 5 and 6 are secured in the same manner as indicated in respect to the bands 7 and 8.

In Figure 4 I have shown other forms of members angular in cross-section which may 80 be used in lieu of the form shown in the principal figures, if desired.

It will be obvious to those skilled in the art that the posts forming the subject-matter of this invention may be made of any length 85 or size desired to adapt them for any particular use or purpose and that such modifications as permitted by the scope of the claims may be made without departing from the spirit of my invention. 90

Having thus fully described my said invention, what I claim as new and desire to secure by Letters Patent, is:

1. A post of the class described formed of two groups of continuous bars of angle iron, 95 one group wound right-hand and the other group wound left-hand, the faces of the several bars of each group being set parallel with the corresponding faces of the other group and the bars of the two groups being 100 secured together at crossing points, substantially as set forth.

2. A post of the class described composed of an outer group of continuous bars of angle iron spirally wound in one direction, an inner group of continuous bars of angle iron spirally wound in the reverse direction, bands positioned between said outer and inner groups, the adjacent faces of the bars of the respective groups being adapted to rest 110

against the outer and inner faces respectively of said bands, and means for securing the bars of said respective groups and said bands together, substantially as set forth.

5 3. A post of the class described comprising members angular in cross section extending in a spiral direction lengthwise of the post, part of said members in one direction and part in the reverse direction, the angles 10 of the members extending in one direction

being substantially parallel with the angles of the members extending in the reverse direction, said members being secured together at their crossing points, substantially as set forth.

15

In witness whereof, I have hereunto set my hand and seal at Washington, District of Columbia, this 12th day of August, A. D. nineteen hundred and twenty-six.

ADOLPH W. MALONE. [L. s.]
